UNITED STATES PATENT OFFICE.

THADDEUS HYATT, OF NEW YORK, N. Y., ASSIGNOR TO ELIZABETH A. L. HYATT, OF SAME PLACE.

ILLUMINATING-GRATING AND BUILDING LIGHTED THEREBY.

SPECIFICATION forming part of Letters Patent No. 257,822, dated May 9, 1882.

Application filed April 19, 1882. (No model.)

To all whom it may concern:

Be it known that I, THADDEUS HYATT, a citizen of the United States, and resident of the city, county, and State of New York, have 5 invented certain new and useful Improvements in Illuminating-Gratings and Buildings Lighted thereby, of which the following is a specification.

In the drawings attached hereto and making 10 part of this specification like letters refer to like parts in all the figures.

Figure 1 represents a prism-glass as ordinarily made for vessels' decks. A is the glass; a, the top surface; b, one slope of the prism; 15 b', the other slope; B, the end or perpendicular side of the prism.

Fig. 2 represents a cluster-lens prism-glass. c c are the lenses.

Fig. 3 represents a metallic grating set with 20 cluster-lens prism glasses. C is the metallic grating; l s, long sides of the grating.

Fig. 4 represents a cluster-lens prism-glass with enlarged reflecting prism-surfaces. b'' b''' are the enlarged surfaces.

Fig. 5 represents a cluster-lens enlarged reflecting-surface prism-glass made with but one reflecting-slope. b⁴ is the reflecting-slope; d, perpendicular or non-reflecting face of the prism.

Fig. 6 represents a single-lens prism-glass.

Fig. 7 represents a single-lens prism-glass with enlarged reflecting prism-surfaces.

Fig. 8 represents a basement and basement-extension lighted by an illuminating area-covering formed of metallic gratings set with cluster-lens prism-glasses made with enlarged reflecting prism-surfaces. D is the basement; E, basement-extension; F, illuminating stoop or area covering; f s, front or street face of 35 the building.

Fig. 9 represents the rear wall of a building above the ground-floor or principal story, the rear wall of the extension, and the opening between the two walls for admitting light into 45 the room. G is the rear wall above the room; H, the rear wall of the extension; I, the light-opening between the walls; J, the room lighted.

Fig. 10 represents a ground-floor or principal story lighted by a curved illuminating-grating

50 roof set with prism-glasses. K is the curved roof.

Fig. 11 represents a ground-floor or principal story lighted by a ventilating step-roof formed of metallic gratings set with lens prism-glasses. L is the step-roof; v', ventilating-flaps set with 55 glass.

The object of my invention is to reflect day-light into the basement and principal story of a building without the necessity of employing 60 "daylight-reflectors."

My improvements are based upon a form of glass represented by Fig. 1, where the whole of the reflecting-power of the prism is confined to two sloping flat reflecting-faces, indicated by the letters b and b', the ends B of the glass 65 being perpendicular, and consequently non-reflecting.

The glass upon which my improvements are based is known to ship-builders as the "prism deck-light." My improvements upon this glass 70 to adapt it to the purposes of lighting buildings are as follows, viz: first, forming the weather-face of the glass with a cluster of lenses, represented by c c, Fig. 2, the effect of the lenses being to enlarge the light-receiving 75 surface of the glass; second, in combination with the lens enlarged receiving-surface, an enlarged distributing-surface, as represented by b''' and b⁴ in Figs. 4, 5, and 7, to compensate for the increased volume of received light 80 due to the lenses; and, third, a lens prism-glass formed with but one reflecting-slope, as represented by Fig. 5, where d is a perpendicular non-reflecting face similar to the ends B. These glasses I call "combination lens and 85 prism-glasses."

My improvement in combining lens prism-glasses with metallic gratings as an illuminating building material consists in setting the lens prism-glasses in the grating with the reflecting-slopes of the prisms in line with the long sides of the grating, as represented in Fig. 3; and my improvements in the method of illuminating buildings consist in constructing the illuminating rear extension-roofs and 90 front area-coverings thereof with illuminating-gratings made in manner as represented by Fig. 3, and combining the same with the build- 95

ings by laying the long-sides of the illuminating-gratings parallel to the face or front wall of the building when for an area-covering, as represented in Fig. 8, and parallel to the rear 5 wall of the building when for a rear-extension roof, as represented in Fig. 11, this method of combining the prism-glasses with the gratings, in combination with the method of combining such gratings with the buildings, cans- 10 ing the reflecting-slopes of all the glasses to act as daylight-reflectors for the purpose of throwing light into the building in the direc- 15 tions required.

H, Fig. 9, represents the rear wall of a ground floor or principal story of a building, and G represents the rear wall of the building above the ground-floor. The wall H is represented as would be required in the making of flat roofs; but in practice this form of roof is avoided in 20 rear extensions, because of the loss of angular light such a mode of construction would entail, as is made evident, by the mass of rays cut off by the portion of the wall H between N and M. Illuminating rear-extension roofs are there- 25 fore, as a general thing, constructed on the principle of a "lean-to," but made in curved form, as represented by Fig. 10; but the form of the prism-glass is not adapted to roofs of the lean-to-type, especially curved roofs. This point 30 I have illustrated by representing the curved roof as set with prism-glasses, the effect of which, where the light-rays fall upon the glasses in the lower portion of the roof, is to reflect the light out of doors, as represented in the figure, 35 where the ray *r* is reflected back on the line *s* and the ray *t* is reflected back on the line *u*. The form of the prism-glass requires that the plane of the roof where such glasses are employed should be practically horizontal; but 40 the conditions connected with rear-extension roofs require them to be in effect lean-to constructions, and a lean-to cannot be a horizontal roof.

My invention to adapt the use of prism- 45 glasses to the construction of illuminating rear-extension roofs consists in making the roof in the step form, as represented in Fig. 11, where *m m* represent the "illuminating-treads" and *v v* the "risers," one or more or all of them being 50 arranged to open, as represented by *v'*. The treads are all slightly inclined, as shown, in order that the light-rays reflected from the prism of one glass may not be interfered with by the projection of a glass in front of it. The 55 effect of this inclination of the treads I have illustrated by the light-rays *n o p q*, each passing clear of the glass in front of it.

The mode hereinabove described of con- 60 structing illuminating step-roofs for the rear

extensions of the ground-floors of buildings ap- 60 plies equally, with proper modifications, to the construction of illuminating step-roofs for the front entrances to buildings.

What I claim as my invention, and desire to 65 secure by Letters Patent, is—

1. Illuminated basements, illuminated base- 70 ment-extensions, and illuminated ground-floors of buildings lighted by metallic gratings set with prism-glasses, when the same are formed with either single or cluster lenses upon the 75 weather-face thereof, the glasses being so set in the gratings and the gratings so combined with the parts of the building to be lighted as that the reflecting-slopes of the prisms shall lie parallel with the front and rear walls of the 80 building, substantially as and for the purposes herein set forth and illustrated.

2. Combination lens and prism-glasses, where 85 the prism portion of the glass is formed of two non reflecting or perpendicular ends and two sloping opposing sides, the internal faces of which receive and distribute the light of the lenses, and combining the same with metallic gratings, substantially as and for the purposes herein set forth and illustrated. 85

3. Combination lens and prism-glasses, where 90 the prism portion of the glass is formed of two non-reflecting or perpendicular ends and two sides, one of which is perpendicular, or nearly so, and the other a slope, the internal face of which receives and distributes the light of the lenses, and combining the same with metallic gratings, substantially as and for the purposes herein set forth and illustrated. 90

4. Combination lens and prism-glasses, where 95 the area of the internal reflecting face or faces of the prism is enlarged, and combining the same with metallic gratings, substantially as and for the purposes herein set forth and illus- 100 trated.

5. An illuminating rear-extension roof con- 105 structed in the form of steps, made of illuminating treads and risers, substantially as and for the purposes herein set forth and illustrated.

6. Illuminating-steps and step-roofs formed 110 of metallic gratings set with combination lens and prism-glasses, substantially as and for the purposes herein set forth and illustrated.

7. Illuminating area-coverings formed of me- 115 tallic gratings set with combination lens and prism-glasses, substantially as and for the pur- poses herein set forth and illustrated.

In testimony whereof I hereto affix my signature in presence of two witnesses.

THADDEUS HYATT.
